UNITED STATES PATENT OFFICE.

JAMES H. SHELLEY, OF BROOKLYN, NEW YORK.

DUST-SEPARATOR.

SPECIFICATION forming part of Letters Patent No. 465,544, dated December 22, 1891.

Application filed April 7, 1891. Serial No. 388,001. (No model.)

To all whom it may concern:

Be it known that I, JAMES H. SHELLEY, of Brooklyn, in the county of Kings and State of New York, have invented an Improvement 5 in Dust-Separators, of which the following is a specification.

The object of this dust-separating apparatus is to prevent dust from passing out into the atmosphere in a mill, thereby avoiding 10 the inconvenience heretofore resulting therefrom and at the same time saving such solid materials as may be useful.

When this invention is used for removing dust from wheat and other grains, the screenings are passed off at one place and the wheat at another and the dust at a third opening, and when the machine is employed as a middlings-purifier the bran is passed off through one spout and the middlings at another.

20 I arrange this apparatus with reference to the creation of dead-air spaces, into which the dust or other solid materials will be projected by their inertia and the current of air passes away from or avoids such dead-air spaces, in 25 order that the solid matter may be free to subside while exposed to little or no atmospheric current. I arrange a double case, in which the air is caused to move circularly, but in opposite directions, and such circulating air is drawn into the interior of the apparatus and through the materials to be separated as such materials fall from one hopper to another.

35 In the drawings, Figure 1 is a central vertical section at the line x' , Fig. 3. Fig. 2 is a similar section at right angles to Fig. 1 and at the line y' , Fig. 4. Fig. 3 is a sectional plan at the line x x , Fig. 1; and Fig. 4 is a sectional plan near the line y y , Fig. 2.

40 The exterior case A is polygonal, or nearly so, and preferably provided with rounding interior corners 2. This case A has a top A' and a hopper-bottom H, terminating with a spout H', and across this case is a shaft B, 45 having a fan-blower C of any suitable character. The air is drawn into the sides of the fan-blower case near the center at 3 and it is projected into the exterior case through the trunk D, and such air circulates around 50 within the exterior case A and between the same and the hanging skirt E, and within this hanging skirt E is a second skirt E', that

does not extend all the way around, and there is an interior separator-case F, the bottom of which is made as a hopper F', leading to a 55 discharge pipe or trunk G, and the upper part of this case F is contracted and extends to the top A' of the case A, and the case of the fan-blower C is within this interior separator-case and the air is projected by the 60 trunk D into the space between the exterior case A and the hanging skirt E, and as it travels around the same and in the corners of the exterior case the current is lessened in its velocity, and in addition to this the rotary motion given to the air in traveling around the case diminishes in a downward direction, because the lower end of the hanging skirt E is open and there is a suction action beneath this lower end of the hanging skirt, which prevents the rotary movement of the air extending 70 down into the hopper, and the air passes around the end 4 of the hanging skirt E, returning in an opposite direction, and the dust and lighter particles are carried by the inertia 75 into the dead-air space 5, through which they fall readily to the hopper H, and the air as it travels in the space 6 between the skirts E and E' returns as it passes around the end 7 of the skirt E', and the particles of dust are 80 carried by their inertia into the dead-air space 8 and also fall into the hopper H, and the air traveling around between the skirt E' and the interior case F is drawn through the opening 10, and the dust is carried by the 85 inertia into the dead-air space 11 and falls into the hopper H. Through the interior case F and opposite to the opening 10 is a second opening 12, and the air is drawn through these openings 10 and 12 into the interior 90 separator-case F, and thence proceeds up to the blower, as before mentioned, so that the air does not pass to the external atmosphere, and the dust is retained within the separator.

95 Within the interior separator-case F there are one or more hoppers and deflectors for presenting the material to be acted upon to the ascending currents of air. The material itself is supplied through a spout K and falls upon a deflector L, and by it the material is spread laterally, and it falls from the edge of this deflector through the ascending current of air upon a hopper M, and such

material is again exposed to the action of the ascending current of air as it falls from the lower edge of this hopper M.

If there is but one hopper M, the material 5 will fall therefrom direct into the hopper N, leading to the discharge-spout P. If there are two or more of the hoppers M, the material will fall from the lower edges thereof upon the deflectors L' and pass down the separator- 10 case, and in so doing the material can be exposed to a current of air as often as may be desired.

In order to direct the currents of air in the most advantageous manner upon the material, I provide beneath each hopper M a conical inclosure R, the upper edge of which is 15 united to the under surface of the hopper M by a band 15, and these conical inclosures R are cut away opposite the openings 10 and 12, 20 and at the sides of the openings 10 and 12 there are plates o o, so that the atmosphere as it is circulated passes through the openings 10 and 12 and into the conical spaces between the inclosures R and the hoppers M, so that 25 such air is drawn with uniformity and regularity up through between the lower ends of the hoppers M and the deflectors L' L as such air proceeds upwardly within the separator-case F, and it is advantageous for the upper 30 and larger edges of the hoppers M not to extend to the interior of the case F, so that there may be a gradual ascending current upwardly within each of the hoppers M and below the conical inclosures of the next hop- 35 per above, and this ascending current of air takes with it the dust and other materials from the descending grain or other substance, and the heavier portions fall within the case F into the hopper F' and is delivered by the 40 spout G.

The valve S is provided in the spout K, and it is pivoted at its upper edge, and there is connected with this pivot a weight S', which may be adjusted upon a lever-arm, so that 45 the valve S will yield to a given weight of material within such spout K, and this will regulate the supply through the spout K and prevent the admission of external atmosphere, and it is advantageous to provide similar 50 valves G' in the spout G and P' in the spout P, and a similar valve may be provided in the spout H'.

It is now to be understood that when grain is introduced by the spout K the dust will be 55 delivered from the spout H' and imperfect grains and seeds will be delivered by the spout G.

If middlings are supplied by the spout K, the purified middlings will pass by the spout 60 P and the bran or dust will pass by the spout H', and the intermediate materials known as "cut-offs" will pass by the spout G.

I find it advantageous to place the interior separator and the hoppers toward one side of 65 the case A, in order that there may be a recess A² in one side of the case extending back to the inner separator-case F, and at this place

the separator-case F is provided with movable doors or slides 18, which cover the openings that lead into the respective hoppers M, so that 70 access is given to these hoppers for cleaning the same should they become obstructed, and the recessed portion A² of the exterior case A forms a partition that prevents the current of air circulating all around within the exterior case A and promotes the efficiency of the dead-air spaces 5 and 19. The dead-air space 19 is below the mouth of the trunk D, and it will be apparent that in the operation of this apparatus the current of air passing out 80 through the trunk D travels around the upper portion of the case A above this dead-air space and its velocity is lessened as it descends, and the dead-air space 19 is of a large size and is very efficient in allowing the solid 85 particles to subside as the current lessens in a downward direction, and it is advantageous to provide an opening between the dead-air space 8 and the dead-air space 19, as shown at 20, so that the dust and solid matter, as it 90 subsides in these two dead-air spaces, will not become clogged between the ends of the skirts E and the case F, but will pass down into the hopper H.

I claim as my invention—

1. The combination, in a separator, of a closed exterior case having a hopper-bottom and a discharge-spout, a blower within the case, having a trunk opening into the upper part of such case, an interior separator-case 100 and a hopper-bottom to the same, with a delivery-spout, the opening of the blower-case taking the air from the interior separator-case, a supply-chute for the material to be acted upon, a deflector and a hopper for presenting the material within the inner separator-case to the upward current of air, and a hanging skirt partially surrounding the inner separator-case, open at the lower edge and at one vertical end for reversing the direction 110 of the current of air and producing a dead-air space, into which the dust is projected, substantially as set forth.

2. The combination, in a separator, of an exterior case with a hopper-bottom and delivery-spout, an interior separator-case having a hopper-shaped bottom and delivery-spout, a blower drawing air from the interior separator-case and discharging the same between the interior and exterior cases, and a hanging skirt 120 partially surrounding the inner case and open at the lower edge and at one vertical end for reversing the direction of the air to produce a dead-air space, into which the dust is projected and falls, substantially as set forth.

3. The combination, in a separator, of the closed exterior case having a hopper-bottom, an interior separator-case with a hopper-bottom and discharge-spout, a blower for drawing the air from the interior case and discharging the same at the upper part between the exterior and interior cases, and two hanging skirts, one within the other and partially surrounding the interior separator-case and open

at their respective ends for reversing the direction of the circulating current of air and producing dead-air spaces adjacent to and beyond the vertical ends, into which the solid materials are projected by inertia, substantially as set forth.

4. The combination, in a separator, of an exterior case, the interior case, a blower to draw the air from the interior case and pass the same into the space between the exterior and interior cases, a supply-spout and valve, a deflector upon which the material falls and is spread, a hopper below such deflector, and a conical inclosure below the hopper, having an opening through the separator-case for the air to be drawn in and pass up through the opening of the hopper and act upon the material as it descends for carrying the dust and light substances upwardly in the interior case, substantially as set forth.

5. The combination, in a separator, of the three hoppers N, F', and H and their respective discharge-spouts, the exterior case A, the interior separator-case F, the blower for circulating the air through the case, and the hanging skirts around the interior case and open at their bottom edges, and the opposite vertical ends for reversing the direction of the

current and producing the dead-air spaces, substantially as set forth.

6. The combination, in a separator, of the interior case F, having a hopper-bottom, the closed exterior case A and its hopper-bottom and discharge-spout, a blower for circulating the air upwardly in the interior case and discharging the same within the upper part of the exterior case, the recessed portion of the exterior case extending to the interior case, there being openings in the interior case with covers or slides, the hopper within the interior case, and the supply-spout, substantially as set forth.

7. The combination, in a separator, of exterior and interior cases with hopper-bottoms and delivery-spouts, a blower to circulate the air upwardly in the interior case and around and downwardly within the exterior case, supply-chute, deflector, and hopper, there being openings through the interior case below the hopper for the passage of the air, substantially as specified.

Signed by me this 28th day of March, 1891.

J. H. SHELLEY.
